PAPER MANUFACTURE

Joseph H. Swan, III, Middletown, Ohio, assignor
to The Gardner-Richardson Company, Middle-
town, Ohio, a corporation of Ohio

Application February 15, 1934, Serial No. 711,301

1 Claim. (Cl. 91—18)

This invention relates to paper manufacture, and more particularly to an apparatus for applying a coating to a sheet of paper.

It is a principal object to provide a compact 5 and simple apparatus for applying coating material to a traveling web of paper such as paper, paper board, and the like.

It is a further object to provide apparatus for applying multiple coatings to a traveling web of 10 paper, and for separately drying each coating, which apparatus is conveniently located and easily accessible for the attention of the operator.

It is a further object to provide apparatus for readily handling and renewing the rolls of paper 15 material.

Other objects and advantages will be apparent from the description and the appended claims.

In the drawing:—

Fig. 1 is a schematic view showing the general 20 arrangement of the coating applying apparatus and the drying apparatus associated therewith;

Fig. 2 is a detail view showing the apparatus for handling the rolls of paper;

Fig. 3 is a view along the lines 3—3 of Fig. 2; 25 and

Fig. 4 is a broken horizontal sectional view along the line 4—4 of Fig. 1.

This invention provides a form of apparatus applicable generally for use in applying coating materials to a sheet of paper or the like, and is more particularly constructed for use in conjunction with the production of a greaseproof paper product and process, such for instance as described in my co-pending application, Serial 30 No. 389,425, filed August 30, 1929, now Patent No. 1,957,369, issued May 1, 1934. As disclosed in said application, a composite greaseproofing coating is applied to a traveling web of paper, the coating being dried following the application 35 of each component layer of the composite coating. In accordance with the present invention, means are provided for applying coating materials, and for thereafter drying the applied coatings, the entire apparatus being conveniently arranged so that it can be easily attended with a minimum of difficulty.

Referring to the drawing which discloses a 40 preferred embodiment of the invention, there is shown at 10 a roll of paper adapted to be rotatably supported and unwound to provide a traveling web of paper 11 which is passed through the coating machine. This roll is preferably wound upon a core which is mounted upon the shaft 12, extending axially beyond the roll face 45 to provide for rotatably supporting the roll. At

opposite sides of the roll, the shaft 12 is mounted in open ended bearing members 13 which are formed as a part of a traveling carriage 14. Each carriage 14 comprises a pair of rollers 15 having double flanges 16 adapted to ride upon a longitudinal track member 17. Each track member is pivotally supported at one end as at 18, upon a suitable pedestal 19. Means are provided for lowering the opposite end of each track, such as the pair of jacks, indicated generally at 20. 5 These jacks may be of any desired construction such for instance as a hydraulic jack, and means are conveniently provided under the control of the operator for simultaneously raising and lowering both such jacks, to thereby raise and 10 lower the ends of the tracks 17.

The purpose of dropping the tracks to the 15 position shown in Fig. 2 is to enable a fresh roll of paper to be conveniently placed upon the tracks. The fresh roll may be brought up to the supports on a truck or the like, and the truck wheeled between the two track members, the roll being directly positioned in the bearing members 13'. Thereafter the jacks are raised to bring the tracks into the level position, and the 20 fresh roll of paper can be unwound and pasted to the expiring roll to be carried through the machine in this manner. Thereafter the expired roll is removed from its journals 13, and the corresponding carriages 14 are manually lifted from the track. The carriages 14 supporting the 25 fresh roll of paper are then moved longitudinally along the track upon the rollers 15' to the operative position as shown in Fig. 1, and the other pair of carriages are then positioned for reception of a fresh roll. Suitable pins 21 cooperating with holes in the track, provide for holding the carriages in desired position.

The traveling web of paper 11 as it leaves the 30 roll 10 passes under a guide roll 25, and into contact with a first coating applying means indicated generally at 26. This comprises a lower roll 27 dipping into a trough 28 which may contain the coating composition to be applied at this point, suitable supply means being provided to maintain a constant level of the composition 35 in this trough. Roll 27 picks up on its surface a film of the coating and carries it into contact with the upper roll 28, which roll transfers a layer of controlled thickness to the web.

The coating composition applied at this point 40 may, for example, comprise essentially rubber latex and casein. The addition of an oil insoluble adhesive, such as casein, to the rubber latex 45 imparts superior characteristics of adhesiveness 50 55

and greaseproofness. Rubber latex has qualities of elasticity and spreading ability and enables a relatively thin coating to be used with satisfactory covering power; it also functions very satisfactorily to lay any fuzz which may be protruding from the surface of the paper and covers up irregularities of the surface. It is also a good moistureproofing and waterproofing agent. Other oil insoluble adhesives may be used, and alkaline material may be added to increase the effective life of the coating. Also a preservative such as formaldehyde may be added. Furthermore the addition of a polysulfide is found to improve the covering power and to prevent deterioration and the formation of pin holes in the coating.

The web of paper with the applied coating thereon then passes around a guide roll 29 and is contacted by one or more revolving rolls 30. The roll or rolls are positively driven against the direction of travel of the paper, and serve to reduce the lines and streaks in the coated surface of the sheet usually produced by the coating press. Each roll may be positioned slightly obliquely with respect to the paper web, as it is found that this oblique positioning tends to improve its functioning.

The web with its partially smooth coating layer next passes into contact with one or more brushes 31. These brushes are preferably reciprocated transversely of the sheet, and serve to further remove whatever streaks or lines still remain after the action of the smoothing roll 30. In some cases it is found that the brushes themselves will leave certain brush marks upon the coated surface of the sheet, and in order to effectively remove such brush marks, a second set of smoothing and spreading rolls 32 may be provided, following the brushes 31. The rolls 32 likewise are preferably driven against the direction of travel of the sheet, and may also be positioned obliquely with respect thereto. Following this combined brushing and smoothing action, it is found that a very superior uniform coating, evenly distributed, and quite free from minute defects or pin holes, is present upon the sheet.

The sheet then passes over a roll 35 and into a drying chamber 36. This chamber is preferably an elongated substantially completely enclosed chamber within which the coated surface of the web is subjected to drying fluid blasts, and in which the web is also subjected to a seasoning treatment. The sheet enters one end of the chamber through a relatively narrow slot 37, and is supported throughout its travel on a series of supporting rolls 38. The drying fluid blasts are directed downwardly upon the upper coated surface of the web from a plurality of supply ducts 39, adapted to discharge the drying medium, usually heated air, directly upon the coated surface of the web. Thus it will be seen that following the smoothing and spreading action, no further contact is had with the coated surface of the web during the drying operation.

By the time the web has reached the remote end of the drying chamber, it is sufficiently dried so that contact with a roll will not damage the surface. At this point the web passes around a turn-over roll 40, which may be slightly crowned to cause centering of the web, and returns through the elongated chamber, supported upon a second series of rolls 41. While no fluid blast is directed upon the web during this pass through the chamber, yet it is in the heated and drying

atmosphere of the chamber, and therefore is subjected to a desired seasoning treatment.

The web leaves the drying chamber at the same end at which it entered, and, passing over guide rolls 44 and 45, it is brought into contact with a second coating applying means 46. This means comprises a lower roll 47 dipping within a trough 48 to which is supplied the coating material desired to be applied at this point. Roll 47 runs in contact with the application roll 48^a, transferring to said roll a film of color to be brought into contact with and applied in a layer of controlled thickness to the surface of the web.

The coating composition applied at this point may comprise a mixture of an oil insoluble adhesive such as casein, a polyhydric alcohol such as glycerin, and a preservative such as formaldehyde. The casein has high greaseproofing qualities and also assists in securely binding the coating to the sheet. The addition of glycerin to the casein imparts characteristics of resiliency to the upper coating, and tends to prevent cracking thereof when the board is bent in the formation of a container for example, without impairing the greaseproofing character of the coating. The composite coating as thus formed therefore comprises a lower layer including the rubber material, and having high flexibility, and an upper layer including the casein, and having high greaseproofness, the two layers being interbonded, the sheet and composite coating thereon serving to maintain the impervious character of the composite coating against disruptive effects in use due to bending and the like.

The web is then preferably brought into contact with a rotary brush 50, revolving against the direction of the travel of the paper, which brush serves to remove the lines or streaks produced at the coating press. After passing around a guide roll 51, the web may then be brought into contact with additional brushes 52, preferably of the reciprocating type, which serve to remove any marks left by the rotary brush 50. Smoothing and spreading rolls may be used at this point if desired, but with the coating of the character described it is usually found that no further smoothing and spreading is required.

The web continues over a guide roll 53, and into the drying chamber 36 for another pass, supported on a third series of supporting rolls 54. Drying fluid blasts from the ducts 55 are directed upon the surface of the web, and it is substantially dried by the time it reaches the remote end of the chamber. A second turn-over roll 56, similar to roll 40, reverses the direction of travel of the web, and it is brought back over the series of rolls 57 through the chamber where it is submitted to further seasoning treatment. It emerges from the chamber at the same end at which it entered, and passes through the nip of rolls 58, 59, which serve to pull the web through the coating and drying apparatus. In any case where, due to the strength characteristics of the web or to increased frictional effects, further driving is desirable, another of the supporting or guide rolls previously described may be positively driven to feed the web forward.

The web then passes around guide rolls 60 and through further coating presses 61 and 62. Any desired material may be supplied by these rolls, such for example as a solution of a metallic salt for the purpose of fixing and precipitating the casein in the top coating described above, which metallic salt may be supplied by the rolls 61. In some cases it is also desirable to apply an over-

lying coating adapted to eliminate taste and odor of the casein, a suitable material for example being sodium silicate, and in such case the rolls 62 may be utilized to apply a thin coating of sodium silicate.

When the web is started through the coating applying machine, it may be threaded by hand through the first coating press, and then brought over guide roll 35. At this point a carrying and 10 threading means is provided for threading the web through the drier chamber. This mechanism preferably comprises an endless traveling rope or carrier member 65 which is looped around roll 35, this roll being positively driven and being 15 therefore adapted to drive the carrier member 65. This carrier travels over the supporting rolls 38, lying directly thereon, and laterally to the side of the traveling web. A convenient attaching means 66 may be clipped to the carrier and to 20 the end of the web during a threading operation which is preferably torn as indicated generally in Fig. 4. The carrier threads the web over the first pass of supporting rolls, and around the turn-over roll and back over the second pass of 25 supporting rolls 41. The attendant then receives the end of the web and manually threads it through the second coating applying press. Thereafter it is brought over guide roll 53 and again attached to the carrier member, to be 30 thereby threaded through the drying chamber and over supporting rolls 54, turn-over roll 56, and supporting rolls 57 successively. The web is then brought out of the machine by the carrier and is manually threaded through the remainder 35 of the coating presses. This endless carrier there-

fore constitutes a very simple and effective means for threading the sheets through the drying chamber.

It will be appreciated that by reason of the present invention the entire operating structure 5 requiring any attention on the part of the operator is positioned close together and in such position that the substitution of a fresh roll, and the operation of all the coating presses can be easily watched by a single attendant. Furthermore, because of this construction, the web as it passes through the elongated drying chamber is subjected not only to drying but to a seasoning treatment which serves to condition and further improve the applied coating layer. 10 15

While the form of apparatus herein described constitutes a preferred embodiment of the invention, it is to be understood that the invention is not limited to this precise form of apparatus, and that changes may be made therein without departing from the scope of the invention which is defined in the appended claim. 20

What is claimed is:

In a coating apparatus for applying a coating of predetermined characteristics to a traveling 25 sheet of paper, the combination of application means, and smoothing means comprising a roll engaging the coated surface of the paper and rotating in a direction opposite to the travel of the paper, a brush following the roll for brushing the 30 coated sheet, and a second roll for thereafter engaging the sheet and rotating in a direction opposite to the travel of the paper. 35
